SAFETY AND SIGNALING DEVICE FOR RAILROADS.

1,095,915.

Specification of Letters Patent.

Patented May 5, 1914.

Application filed October 23, 1913. Serial No. 796,759.

To all whom it may concern:

Be it known that I, DIMOND C. NEWTON, a citizen of the United States, and a resident of the city of Owego, county of Tioga, and 5 State of New York, have invented a new and useful Safety and Signaling Device for Railroads, of which the following is a specification.

My invention is adapted for use in connection with all railroad lines in which semaphores or similar signaling devices are used, and it is the purpose of the invention to supplement semaphore apparatus with additional electrical appliances so that it will be 10 impossible for a train to pass a semaphore set for danger irrespective of any act on the part of the engineer or motorman because the apparatus will automatically bring the train to a stop, thus eliminating all danger 15 arising from lack of attention on the part of the engineer or motorman, or inability to see the semaphore, owing to fog, smoke or other obstruction, and perhaps sudden illness which has been known to incapacitate an 20 engine driver.

Generally stated, the invention consists in supplementing the semaphore apparatus with devices on the roadbed which co-act with other devices carried by the locomotive, 25 electric car, or other engine, so constructed and coöperating that when the semaphore is set for danger, the passage of the engine over the devices located in the roadbed will close a battery circuit sufficiently powerful to 30 actuate the automatic brake mechanism carried by the engine, and the construction and arrangement are such that the release of the brake mechanism and consequent stopping of the train are entirely automatic, requiring 35 no act to be performed nor thought exercised by the engineer or motorman.

The drawing hereof illustrates diagrammatically the construction and method of operation of the parts. They are enlarged 40 and somewhat separated from each other that the construction and method of operation may be more plainly noted.

1 represents an electric bell provided with suitable operating devices which latter are 45 preferably inclosed in a suitable casing 2.

3, 3' are suitable conductors connecting the bell with suitably constructed shoes 4, 4'.

5 is a magnet connected by conductors 6, 6' with the conductors 3, 3' respectively.

55 When energized the magnet exerts its attrac-

tive force upon the lever 7 which is normally retracted by a spring 8. This lever when drawn downwardly actuates a locking pawl 9 which releases a drum 10 or its equivalent, whereby through appropriate apparatus 60 and in a manner well understood, the brake system of the train is called into action.

11, 11' are set screws for proper adjustment of the lever 7.

All of the parts thus far described are 65 mounted upon and carried by the locomotive, electric car or other engine.

12 and 13 are rails of the track which may be of any preferred construction and supplied with the usual semaphore equipment. 70

15 and 16 are contact rails, preferably laid in the track between the rails 12 and 13 and so located and of such length as to properly register with and engage the contact shoes 4, 4' carried by the locomotive or 75 other engine.

17 is a battery of such power as will ring the bell 1 carried by the engine and also operate the brake mechanism. This battery may be the same battery that actuates the 80 semaphore, its power being sufficiently increased to perform its added duties if found necessary, or it may be a separate and distinct battery from the semaphore battery, the circuit of which will be opened and 85 closed by the position of the semaphore arm.

18 is the semaphore arm mounted as usual upon the semaphore post 19 and provided with connecting rod 20, or its equivalent, whereby through the contact plate 21 the circuit is closed and broken. 90

22 is a conductor connecting one end of the battery with the semaphore contact plate 23.

24 is another conductor connecting the 95 other semaphore contact plate 25 with the contact rail 15.

26 is a resistance placed between the conductor 22 and the conductor 24.

27 is a conductor connecting the other end 100 of the battery with the contact rail 16.

The operation is as follows: When the semaphore arm is dropped, i. e., not as shown in the drawing, then there will be no connection between the semaphore contacts 23 and 25, owing to the separation of the plate 21 therefrom and no current can pass that point. The parts being in this position, as the locomotive, electric car or other engine, proceeds along the track in the direction 105 110

indicated by the arrow, the contact shoes 4, 4' will engage with the contact rails 15 and 16, whereby in a manner well understood the circuit from the battery will be closed as follows: from the lefthand end of the battery through conductor 22, through resistance 26, through conductor 24 to contact rail 15, through contact shoe 4 and conductor 3 to the bell, through conductor 3' to contact shoe 10 4', thence to contact rail 16 and conductor 27 back to the other pole of the battery. Owing to the inter-position of the resistance the current passing through the circuit just described will be not powerful enough to 15 energize the magnet 5 sufficiently to actuate the brake controlling lever 7 and the result will be that the bell in the cab of the locomotive or motorman's apartment, as the case may be, will ring, thus giving notice that 20 the semaphore being set for safety, presumably the track is clear and that the train may proceed. If, however, the semaphore arm 18 is set for danger, *i.e.*, elevated into a horizontal position, as shown in the drawing, when by the advance of the engine the contact shoes 4, 4' have made engagement with the contact rails 15, 16, a different circuit will be closed because the elevation of 25 the semaphore arm will have brought the conductor plate 21 into contact with the semaphore terminals 23 and 25, thus making electrical connection between them and now a circuit will be established as follows: from the lefthand end of the battery through 30 conductor 22 to semaphore terminal 23, through connecting plate 21 to semaphore terminal 25, through conductor 24 to contact rail 15, through shoe 4 and conductor 3 to the bell, and now the resistance having been 35 cut out, the current is so powerful that it will pass from conductor 3 through conductor 6 to the magnet coil 5 and from the other end of the coil through conductor 6' to conductor 3', thence through shoe 4' to track 40 rail 16 and thence through conductor 27 back to the other pole of the battery and this current will be so powerful that the magnet 5 will be energized and bar 7 drawn downwardly, thus releasing the locking pawl 9 of 45 the drum 10, or its equivalent, which acting through appropriate mechanism in a manner well understood, will bring the brake mechanism of the train into action, causing it to come to a stop and at the same time the 50 bell 1 will ring, thus causing the engineer or motorman to be observant to ascertain what is taking place.

The various parts of the apparatus described and shown will of course be provided with the usual attachments or devices to render their operation efficient and reliable, as, for example, the battery, whether the 55 semaphore battery or another, may be placed

between the track rails, or by the side thereof, as preferred, and should be protected 60 against the elements by suitable housing, also the contact rails 15 and 16 may beneficially be covered in any preferred manner to protect them against ice and snow, and the contact shoes 4, 4', will of course be correspondingly constructed to assure suitable electrical connection between them and the contact rails. 70

It will be obvious to those who are familiar with such matters that the details of construction may be changed without departing from the essentials of the invention. I therefore do not limit myself to the details shown and described. 75

I claim:

1. Railway safety apparatus embodying track rails, stationary contact devices in the roadbed, a semaphore and a switch controlled thereby, a battery and an electrical conductor connecting one end of the battery with the said semaphore-controlled switch, and a conductor connecting said switch to one of the contact devices, a resistance interposed between the above-mentioned conductors, another conductor connecting the other end of the battery with the other contact device, and a signaling device, automatic brake mechanism and circuit-closing devices carried by the engine, said circuit-closing devices controlling said brake mechanism and signaling device and adapted to coöperate with said stationary contact devices, said signaling device requiring less current than the brake mechanism, whereby it is operated at all times when the circuit-closing devices are in contact with the stationary contact devices. 90

2. Railway safety apparatus embodying stationary contact devices located in the roadbed, a track signaling device, a battery, conductors connecting the two poles of the battery with the respective contact devices, a resistance in the circuit and means to shunt the resistance when the signal is set for danger, and a signaling device, automatic brake mechanism and circuit-closing devices all carried by the engine and in operative relation to the said stationary contact devices, whereby the signaling device carried by the engine is operated when the said resistance is in circuit and the brake mechanism and the signaling device carried by the engine are both operated when the said resistance is shunted. 105

In testimony whereof I have signed my name to this specification in the presence of two subscribing witnesses.

DIMOND C. NEWTON.
